UNITED STATES PATENT OFFICE

2,453,800

KNIFE RACK

George Henry Lowell, Jr., South Portland, Maine

Application June 15, 1945, Serial No. 599,710

2 Claims. (Cl. 211—60)

1

This invention relates to improvements in kitchen appliances and more particularly to a rack for supporting different types of knives, matches and various utensils.

An important object of the invention is to provide a kitchen appliance whereon knives of different types can be supported in clear view and readily accessible at all times.

A further object of the invention is to provide a wall attachable appliance for conveniently supporting various and divers kitchen utensils in a convenient, visible and readily accessible manner.

Still a further object of the invention is to provide an appliance of the character stated which can be inexpensively manufactured and mounted without skilled assistance.

These and various other important objects and advantages of the invention will become apparent to the reader of the following description.

In the drawings:

Figure 1 is a fragmentary front elevational view.

Figure 2 is a top plan view of the appliance.

Figure 3 is a fragmentary rear elevational view.

Figure 4 is a fragmentary vertical sectional view taken on a line 4—4 of Figure 1.

Figure 5 is a fragmentary vertical sectional view taken on line 5—5 of Figure 1.

Figure 6 is a horizontal sectional view taken on line 6—6 of Figure 5.

Referring to the drawings wherein like numerals designate like parts it can be seen that reference character A denotes a wall such as the wall of a kitchen, while numeral 5 generally refers to the kitchen appliance.

The appliance consists of a horizontal elongated member 6 which forms a backing strip.

An intermediate panel 7 is provided and has a raised portion (see Fig. 2) denoted by numeral 8, this raised portion and the portion of the panel 7 underlying the same being chamfered as at 9. Laterally of the raised portion 8, the panel 7 has a horizontal cleat 10 against which the handles B of knives can bear.

A front panel 11, somewhat wider than the panel 7 and the strip 6 has a raised portion 12, rising to the height of the raised portion 8 and bridging the side portions of this chamfered side to allow for a narrow knife receiving slot 13.

The back side portion of the front panel 11 opposed to the adjacent end of the panel 7 has its edge portion bevelled as at 14. The opposed portion of the panel 7 is chamfered as at 15, thus defining a slot 16 for the reception of knife blades.

2

Screws 17 are provided and disposed through the portion of the panel located above the slot 16 and driven into the wall A for supporting the appliance. Screws or the like 18 are disposed through the upper portion of the upstanding part 12 and into the upstanding portion 8 of the panel 7 to secure these parts together.

It will be noted that the upper edge of the raised portion 12 of the panel 11 is cut away somewhat so that a blade can be readily engaged against the exposed upper portion of the raised part 8 of the panel 7. (See Fig. 1.)

A cleat 19 is disposed horizontally on the panel 11 just below a hollow match receptacle 20 which is glued or otherwise secured to the upstanding portion 12 of the panel 11. On the cleat 19 are a plurality of small utensil supporting hooks 21 and screws 22 are disposed through the end of the cleat and into the panel 11. Additional screws 23 may be employed for securing the panel 11 to the panel 7.

As is apparent in Figure 6, the chamfer 15 of the panel 7 extends entirely across the panel 7 and merges with the chamfer 9.

25 A pencil supporting grooved ledge 24 is provided at the outside of the match receptacle 20.

It can be seen now, that paring knives and other small knives can be inserted down the bevel 14 and slot 16 and there supported, with the handles bearing against the strip 10 until needed.

30 Larger knives can be disposed in the slot 13 and supported with their handles only visible. Of course matches or other small elements may be disposed in the receptacle 20. This receptacle 35 may be used for containing tooth picks, and of course a pencil may be supported on the ledge 24.

Various small utensils may be suspended from the hooks 21 and if desired a calendar may be secured to the depending portion of the panel 11.

40 The entire appliance can be manufactured from wood, plastic or some other inexpensive and readily obtainable material.

45 While the foregoing description sets forth the invention in specific terms, it is to be understood that numerous changes in the shape, size and materials may be resorted to without departing from the spirit and scope of the invention as claimed hereafter.

Having described the invention what is claimed 50 as new is:

1. A kitchen appliance comprising a back panel, a front panel connected to the back panel and overlapping at its upper portion, the lower portion of the back panel, the upper inner portion 55 of the front panel being beveled, the lower por-

portion of the back panel opposed to the beveled portion being chamfered to allow for the disposition of cutlery blades between the opposed portions of the panels.

2. A kitchen appliance comprising a back panel, a front panel connected to the back panel and overlapping at its upper portion, the lower portion of the back panel, the upper inner portion of the front panel being beveled, the lower portion of the back panel opposed to the beveled portion being chamfered to allow for the disposition of cutlery blades between the opposed portions of the panels, the upper portion of the back panel being provided with a horizontal cleat 10 against which cutlery handles can bear. 15
